UNITED STATES PATENT OFFICE.

GEORGE O'KILL STUART CONWAY, OF STONEFIELD, CANADA, ASSIGNOR
OF ONE-HALF TO WILLIAM HERBERT CLARENDON MUSSEN, OF MON-
TREAL, CANADA.

CATTLE-GUARD.

No. 798,091.

Specification of Letters Patent.

Patented Aug. 29, 1905.

Application filed August 27, 1904. Serial No. 222,462.

To all whom it may concern:

Be it known that I, GEORGE O'KILL STUART CONWAY, of Stonefield, county of Argenteuil, Province of Quebec, Canada, have invented 5 certain new and useful Improvements in Cattle-Guards; and I do hereby declare that the following is a full, clear, and exact description of the same.

The invention may be said, briefly, to consist of certain improvements in the means effecting an operative connection between a tread and a lifting-fence whereby the movable fence is supported substantially in equilibrium and is more easily and more quickly operated. 15

For full comprehension, however, of the invention reference must be had to the accompanying drawings, forming a part of this specification, and wherein—

20 Figure 1 is a plan view of my improved cattle-guard in place ready for operation. Fig. 2 is a vertical sectional view taken on line A A, Fig. 1. Fig. 3 is a detail perspective view of the base-leaf of the fulcrum-hinge of my improved cattle-guard. Fig. 4 is a detail perspective view of a fulcrum bracket or lever acting in conjunction with such base-leaf forming the upper leaf of the hinge. Fig. 5 25 is a vertical sectional view of the guard, taken on line B B, Fig. 2. Fig. 6 is a detail side elevation of the connecting-plate whereby the lifting-fence is connected to the pivot-bar of my improved cattle-guard, and Fig. 7 is a detail side elevation of the counterpoise-lever

30 forming a part of the operating mechanism. Fig. 8 is a horizontal sectional view taken just beneath the tread and illustrating particularly the means for operatively connecting the tread to the fence and pivotally connecting the former to the base, such means being shown in plan view; and Fig. 9 is a perspective view with a portion of the tread in place. Fig. 10 is a perspective view of the bracket by which one of the fulcrum-rods is rotatably secured to 35 the under side of the tread.

40 My improved lifting-fence is made, preferably, of metal and in three sections, adapted to be located, respectively, one, *d*, between the rails *c c* of the track and the others, *e* and *f*, one at each side of the track. Each of 45

50 these sections consists of a series of bars or arms *b*, each having secured rigidly to one end thereof a plate *g*, having a square opening *h* therein and a set-screw *i*, adapted to secure

the arm to a square pivot-bar to be presently further alluded to, while the opposite ends of the bars or arms of each fence-section are connected together by a corrugated fence-rail *k*.

The bars *b* of each fence-section are mounted, through the medium of the plates *g*, upon a pivot-bar *l*, (before mentioned,) which extends from side to side of and beneath each section of the tread of my improved cattle-guard, thereby connecting together the members of each section. 65

My improved tread consists of three sections *u v w*, located similarly to the fence-sections and each consisting of a series of treads *m*, of substantially triangular cross-section, connected together at their ends (which are 70 preferably beveled) by straps *n*, secured to the latter and further secured together off of their centers by a cross-support *o*, to which the bars *m* are secured, preferably by bolts *p*. Each of these tread-sections *u*, *v*, and *w* 75 is fulcrumed upon a common base-tie *r*, suitably supported and ballasted upon timbers *s*, on one end of each of which is supported a stop-block *t* for limiting the tilt of the treads. 80

A fulcrum is provided in each case by hinge-leaf *2*, secured rigidly to the cross-support *o* by bolts *p* or otherwise and hinged, as at 3, to one end of a base hinge-leaf *4*, secured rigidly upon the base-tie *r* and having a series of lugs *5* formed integrally with the opposite 85 end thereof.

Each fence-section is operatively connected to its corresponding tread-section by a pair of cam-plates *6*, projecting laterally from the lower portion of each fence-section, such cam-plates being slotted, as at 7, and having an upwardly-inclined cam-surface *8*. A hinge-lever *9* is fulcrumed at one end through the medium of a square fulcrum-bar *10* to the upwardly-projecting lugs *5* upon the base hinge-leaf *4*, such fulcrum-bar extending beneath the three members of the tread and also beneath the rails *c* and through square holes in the series of hinge-levers *9* in order to cause 90 the fence-sections to move collectively and in unison when any one of the tread-sections is trodden upon, while a pair of counterpoise-levers *12* are mounted upon the opposite ends of this bar, the function of the latter being to normally yieldingly maintain the treads and 95 fence-section in their normal position. 100

Each of the hinge-levers *9* is slotted longitudinally, as at 13, and each of the upper

hinge-leaves 2 has a laterally-projecting stud-pin 14 upon one end projecting into the slot 13 in the hinge-lever 9 adjacent thereto.

A stud-pin 15 upon each of the hinge-levers 5 acts as a support for the fence members which are supported thereon through the medium of the cam-plates 6, and a second stud-pin 16 upon the end of the hinge-lever projects into the slot 7 of the cam-plate.

10 The operation of my improved cattle-guard is as follows: Upon the cattle treading upon the end of either tread-section adjacent to the roadway α such tread will be tilted and each fence-section will be caused to suddenly rise 15 to a substantially vertical position and in so doing will strike the cattle in the face. This action is caused as follows: When cattle step upon either of the tread-sections α , such tread-section will tilt upon its fulcrum-point 3 and 20 through pin 14 and the walls of slot 13 raise the lever 9, which in turn through stud-pins 15 and 16 and cam 8 and the walls of slot 7 throws up the fence-section contiguous thereto. Simultaneously the lever 9 rotates and 25 the fulcrum-bar 10 and the other levers 9 are raised, thus causing them through their pin projections 15 and 16 to turn the cam-plates 6 upwardly and raise all the fence-sections in unison. Incidentally the other tread-sections 30 are lowered.

The tread-sections as they lie in their horizontal position are almost in equilibrium, but with a slight preponderance of weight in the portion on the side of the fulcrum-point opposite to the roadway α , and therefore in the rear. When the forward end of the tread has 35 been relieved of the weight of the cattle, the preponderance of weight in the rear will bring the guard back to its normal position.

40 What I claim is as follows:

1. In a cattle-guard the combination with a single tread pivotally supported near its center upon a stationary base and adapted to have one end tilted below the other, a fence 45 pivoted at a point between the ends of such tread and such fence being adapted to be raised and lowered, of means effecting an operative connection between the tread and fence whereby the latter is raised toward the lowered end 50 of the tread upon the tilting of the said tread.

2. In a cattle-guard, the combination with a tiltable tread, a fence adapted to be raised and lowered, and a base supporting the tread,

of a laterally-projecting cam upon the fence, means pivotally connecting the tread to the 55 base, and a hinge-lever pivotally connected at one end to the base, at its opposite end to the laterally-projecting cam upon the fence, and between its ends to the tread, for the purpose set forth.

3. In a cattle-guard, the combination with a tiltable tread, a fence adapted to be raised and lowered, and a base supporting the tread, of a laterally-projecting cam upon the fence, said cam being slotted at right angles to the 60 fence, laterally-projecting stud-pins carried by the tread, a hinge-lever pivotally connected at one end to the base said hinge-lever being slotted and such slot being adapted to receive the stud-pins upon the tread, and a stud-pin 70 mounted rigidly upon the free end of the lever and projecting into the slot in the cam, substantially as described and for the purpose set forth.

4. In a cattle-guard, the combination with a tiltable tread, a series of fence-sections adapted to be raised and lowered, and a base supporting the tread, of a laterally-projecting cam-plate 6 upon each fence-section such cam-plates being slotted at right angles to the 75 fence-sections, a series of hinge-levers 9 each having a pair of studs 15 and 16, the latter being at one end thereof and projecting into the slot of one of the cam-plates, the other, 15, being in position to act upon the cam-surface 80 of said plate, the opposite end of each hinge-lever having a square opening and the body of such lever between its ends being longitudinally slotted, a series of upwardly-projecting lugs 5 rigidly secured to the base and 85 having circular openings in their upper ends, a square fulcrum-bar 10 passing through such lugs and through the square openings in the hinge-levers, a pair of counterpoise-levers 12 one mounted upon each end of the fulcrum-bar, and the tread having a series of laterally-projecting stud-pins 14 adapted to project into the slots in the levers, substantially as described and for the purpose set forth.

In testimony whereof I have affixed my signature in presence of two witnesses.

GEORGE O'KILL STUART CONWAY.
